United States Patent Office.

NICHOLAS S. VEDDER, OF TROY, NEW YORK.

Design No. 2,789, dated August 6, 1867.

DESIGN FOR THE DOORS OF A STOVE.

The Schedule referred to in these Letters Patent and making part of the same.

TO ALL WHOM IT MAY CONCERN:

Be it known that I, NICHOLAS S. VEDDER, of the city of Troy, in the county of Rensselaer, and State of New York, have invented or produced a new and original Ornamental Design for Doors of a Cooking-Stove, of which the following is a full and exact description, reference being had to the accompanying photographs, in which—

Figure 1 represents the smaller, and

Figure 2 the larger of two doors which embody my said design.

The design for the smaller door consists of a vertically-ribbed surface, *a*, and two horizontally-grooved surfaces *b b*, surrounded by an ornamental moulding, *c*, on the middle of a plane panel, *d*, having right-angle ribbed corner pieces *e e e e*, the whole shaped and arranged together so as to appear as represented by fig. 1 of the aforesaid photographs. And the design for the large door consists of horizontal ribs *f*, short alternating upright ribs *g*, and a latch, *h*, on the panel, and two angular strap-hinges *i i* on the broad, flat, raised border *j*, the whole being formed and disposed so as to present the same appearance as that represented by fig. 2 of the photographs.

What I claim as new, and of my invention or production, and desire to secure by Letters Patent, is—

The design for doors of a cooking-stove herein set forth and shown.

NICHOLAS S. VEDDER.
